(57) **CLAIM**

The ornamental design for an embryo slide culture dish, as
shown and described.

DESCRIPTION

FIG. 1 is a perspective view showing the design of a cover
portion of an embryo culture dish, which dish is comprised of
a cover portion and a base portion;

FIG. 2 is a right side view of the cover of FIG. 1, it being
understood that the left side view thereof is identical;

FIG. 3 is a front end view of the cover of FIG. 1, it being
understood that the back end view thereof is identical;

FIG. 4 is a bottom view of the cover of FIG. 1; the broken lines
in FIG. 4 represent environmental subject matter and form no
part of the claimed design;

FIG. 5 is a top view of the cover of FIG. 1;

FIG. 6 is a perspective view showing the design of a base
portion of an embryo culture dish; the broken lines in FIG. 6
represent environmental subject matter and form no part of
the claimed design;

FIG. 7 is a bottom view of the base portion of the embryo
culture dish of FIG. 6;

FIG. 8 is a right side view of the base portion of the embryo
culture dish of FIG. 6, it being understood that the left side
view thereof is a mirror image of the right side view;

FIG. 9 is a front end view of the base portion of the embryo
culture dish of FIG. 6;

FIG. 10 is a back end view of the base portion of the embryo
culture dish of FIG. 6; and,

FIG. 11 is a top view of the base portion of the embryo culture
dish of FIG. 6; the broken lines in FIG. 11 represent environmental
subject matter and form no part of the claimed design.
